UNITED STATES PATENT OFFICE.

WILLIAM D. HUGHES, OF WASHINGTON, DISTRICT OF COLUMBIA.

DOOR-KNOB.

SPECIFICATION forming part of Letters Patent No. 241,664, dated May 17, 1881.

Application filed March 21, 1881. (Model.)

To all whom it may concern:

Be it known that I, WILLIAM D. HUGHES, of Washington, in the District of Columbia, have invented new and useful Improvements 5 in Door-Knobs; and I do hereby declare that the following is a full and accurate description of the same.

The principal desiderata of a door-knob are, first, complete adjustability on the spindle to accommodate doors of varying thicknesses without weakening the spindle by perforating it; second, secure attachment to the spindle, so that it will not come loose therefrom under the various strains to which it will be subjected in use; third, compactness and small number of parts; fourth, durability and non-liability to derangement; fifth, cheapness. All of these conditions are satisfied in my invention.

I am aware that door-knobs have heretofore been made adjustable on the spindle, so as to avoid the employment of washers, and, in some instances, without perforating the spindle, and thereby weakening the same. I therefore do not claim, broadly, a method for making a knob 25 adjustable without weakening the spindle, but confine myself to the particular means and the arrangement of such means.

To this end my invention essentially consists in a knob-spindle provided at one or both 30 ends with a screw-thread cut on its corners, so as to leave one or more blank spaces running lengthwise along said spindle longitudinally; a knob provided with a female screw fitted to the screw upon said spindle, so that it may be adjusted or moved to any point on the 35 same by revolving it thereon; a collet fitted to the flat portion of said spindle, so as to slide freely but not to revolve thereon, and a device for rigidly connecting said knob and collet when 40 they have been adjusted or moved to the proper point on the spindle, whereby said knob and collet will mutually restrain each other from motion independent of the spindle, either revolving or sliding.

45 That others may fully understand my invention, I will particularly describe it, having reference to the accompanying drawings, wherein—

Figure 1 represents my invention in perspective. Fig. 2 is a central longitudinal sec-

tion of the same. Fig. 3 is a transverse section through the collet. Fig. 4 represents a modification.

A is the knob, which may be constructed of any suitable material. It is constructed with 55 an interior cavity, b, the surface whereof is provided with a female screw, c, to receive the corresponding screw-thread of the spindle D. In practice it is not required that the screw-thread c shall extend throughout the whole 60 length of the cavity b; but that may be according to the taste or desire of the manufacturer or user. By placing the screw-thread within the knob it is thereby united directly with the spindle, and the longitudinal or pulling strain 65 to which the knob is subjected in use is transferred directly to the spindle, and not through some intermediate connecting part. This is a point of great practical importance, because the strains referred to are by far the most numerous and trying to which a door-knob is 70 subjected.

The spindle D is commonly made of a square bar of iron or steel, the screw-thread being cut upon the corners only of said bar, and thereby longitudinal flattened spaces are left 75 along the threaded part. It may sometimes, however, for some reason, be desirable to provide a greater area of screw-thread, and in that case the spindle may be cylindrical along 80 the threaded part and the threads removed along a line on one side, either flattening the spindle along said line or making a groove along the same. These ways, however, are merely well-known alternatives, and do not 85 affect the invention. The portion of the spindle D which is exterior to the knob when the latter is in proper adjustment is within the lock or door, as the case may be.

A collet, E, is fitted to slide upon the spindle D, being fitted to the flat parts of the surface of said spindle, so that it cannot revolve on the same, and when the knob is brought to the proper adjustment is rigidly secured to said collet by a screw, G, or some equivalent 90 and proper device, and when so united the knob cannot again revolve nor the collet slide, and they mutually lock each other in position. The rotary strains in operating the lock are then transferred to the spindle through the 100

collet E, while the more severe and frequent pulling strains above mentioned are transmitted directly to the spindle by means of the screw-thread *c*.

5 For purposes of economy in manufacture, as well as for aesthetic reasons, the collet E is concealed within the cavity *h* at the base of the knob, as shown, and the connecting device is most conveniently a screw, G, which penetrates 10 through the rim of the knob exterior to the cavity *h* and engages with the collet E. I prefer to have the screw G penetrate the collet, as shown in Figs. 2 and 3, because I can most conveniently provide a desirable depth of metal 15 to receive the screw in that way; but it may be done in other ways—as, for instance, as shown in Fig. 4, where the female screw is in the rim of the knob, and its point engages with the collet, if desired. In the latter case the collet 20 will be constructed with one or more notches, *i*, to receive the point of the screw G and be securely locked thereby.

The pitch of the screw-thread cut upon the spindle is usually about one-twentieth of an 25 inch, and therefore each revolution of the knob will move it longitudinally one-twentieth of an inch.

The collet E may be provided with one, two, three, or four apertures, *g*, threaded to receive 30 the screw G, and the longitudinal adjustment of the knob may therefore be within one-fourth of one revolution, or by stages of one-eighth of an inch. For the cheaper grades of locks adjustments of one-twentieth or one-fortieth of an inch will be all that will be required.

In manufacturing these knobs the only tool-work that will be required in finishing them will be in cutting the screw-threads and drilling 40 for the same, because there are no joints exposed to view which will require to be carefully fitted, and the parts may be cast with proper dimensions to fit with sufficient accuracy when the joints are concealed. Of course 45 such an amount of exterior finish as may be desirable can be applied; but such finishing will be entirely with a view to ornament, and without reference to utility.

When placing this knob in position the adjustment is obtained directly and without removal of any of the parts from the door. The spindle being inserted with one knob already fixed by riveting or otherwise, the knob A is screwed upon the projecting end of said spindle 55 with the collet in proper position in the cavity *h*, and the knob is revolved until it is arrested by contact with the door or plate of the lock. It is then turned backward until the screw G is opposite the first reached of the 60 apertures *g* in the collet, and said screw is then screwed home therein and the adjustment and

fastening is complete. An ordinary rose may be employed, if desired.

Aside from the cheapness and easy adjustability of this device it will be permanent and 65 durable.

It has been found out by experience in mechanics that intermittent and irregular pressures and jars acting upon the end of a set-screw will invariably cause the same to become loose 70 and backed out, and it is therefore necessary to insert the screw G into the spindle, as in the common locks now in the market, or to employ some other mode, whereby the pressure acting upon the screw will act against its sides and 75 not against its end. For that reason I employ the collet E.

The screw G may be provided with a conceal head, and when forced through the collet E until its end rests upon the spindle D the 80 revolution of said screw thereafter will force the collet and spindle into hard contact, and will also draw the knob-rim into hard contact with the collet, so that by the single action of the screw G the spindle, collet, and knob are 85 mutually tightened upon each other and lost motion prevented.

Having described my invention, what I claim as new is—

1. To constitute an adjustable door-knob, 90 the combination of a knob, A, provided with a female thread, a spindle, D, fitted to said thread, so that said knob may be screwed upon said spindle, a collet, E, fitted to slide upon said spindle, but not to turn thereon, and a 95 clamping device, whereby said knob and collet may be rigidly secured together, substantially as and for the purpose set forth.

2. The knob A, with an interior screw-thread, *c*, and a cavity, *h*, in its base, and a spindle, 100 D, provided with a male thread fitted to said screw-thread *c*, and one or more longitudinal flat portions, as described, combined with a collet, E, fitted exteriorly to be concealed in said cavity *h*, and interiorly to said flat portions of the spindle D, so as to slide but not to turn thereon, and a clamping-screw, G, whereby said knob and collet mutually lock each other in position upon said spindle, substantially as set forth.

3. The collet E, with the aperture *g* penetrating to its central orifice, the spindle D, and knob A, all as described, combined with the screw G, provided with a conical head, where-by all of said parts are tightened upon each other.

In testimony that I claim the above as my invention, witness my hand.

W. D. HUGHES.
